[57] CLAIM

The ornamental design of a mounting leg for a fifth wheel hitch, as shown and described.

DESCRIPTION

FIG. 1 is a perspective view of the mounting leg for a fifth wheel hitch in full line and the hitch head and mounting brackets in phantom line;

FIG. 2 is a right side elevational view of the mounting leg, the left side elevational view being a mirror image thereof; FIG. 3 is a front elevational view of a mounting leg, the rear elevational view being a mirror image thereof;

FIG. 4 is a top plan view of a mounting leg; and, FIG. 5 is a bottom plan view of a mounting leg.

The phantom lines in the drawing are for illustrative purposes only and form no part of the claimed design.
